UNITED STATES PATENT OFFICE.

BENJAMIN EDWIN MEACHAM, OF LORAIN, OHIO, ASSIGNOR TO AMERICAN STOVE COMPANY, OF ST. LOUIS, MISSOURI, A CORPORATION OF NEW JERSEY.

THERMOSTATIC FUEL-REGULATING DEVICE FOR GAS-OVENs.

1,339,964.

Specification of Letters Patent. Patented May 11, 1920.

Application filed July 7, 1919. Serial No. 309,244.

To all whom it may concern:

Be it known that I, BENJAMIN E. MEACHAM, a citizen of the United States, residing at Lorain, in the county of Lorain and State of Ohio, have invented certain new and useful Improvements in Thermostatic Fuel-Regulating Devices for Gas-Ovens, of which the following is a specification, reference being had therein to the accompanying drawing.

This invention relates to improvements in thermostatic fuel controls for gas-heated ovens, and the primary object of the invention is to provide an adjustable mechanism for maintaining the heat within the oven at a predetermined temperature.

It is well-known that different kinds of cooking requires different degrees of heat, some articles requiring to be cooked slowly and others rapidly.

In the regulating devices heretofore known to me for accomplishing this purpose, such for instance, as shown in my Patent No. 1,236,335, dated August 7th, 1917, the adjustment for maintaining the desired degree of heat is accomplished by adjusting the fulcrum of the thermostatic mechanism.

The object of my present invention is to regulate and control the heat degree in the oven by a relative adjustment of a gas-outlet and a valve, one of the members being controlled by a thermostat, which, in turn, is actuated by the heat in the oven generated by the burner to which the gas flows through the controlled gas-outlet.

A further object of my present invention pertains to the particular construction of the devices for controlling the outlet to an oven burner.

40 In the accompanying drawings—

Figure 1 is a perspective view of a stove showing my invention applied thereto.

Fig. 2 is a section through the oven, showing my improved device in side elevation.

45 Fig. 3 is a vertical sectional view through the gas-controlling members of my improved device.

Referring now to the drawing, in which similar reference characters designate the same parts, 1 is a stove and 2 the oven thereof.

In carrying out my present improvement, I provide a suitable thermostat 3, which has its upper end 4 suitably connected to a 55 casting 5. The upper end of this casting is

suitably bolted, as shown, to the wall of the oven 2. The lower end 7 of the casting 5, is attached to the inlet end 8 of a burner 9, for heating the oven. Preferably, the inlet end 10 of the burner 9 is deflected upward out of line with the burner 9.

A gas-supply pipe 11 is provided and in the form here shown, its lower end is connected with the casting 5, by an outwardly extending embracing arm 12. The lower end of the pipe 11 has a gas-outlet comprising a stationary nipple member 13, and an adjustable nipple-member 14, which telescopes the member 13, by its screw-threads as shown, so that the member 14 as it is rotated, will move in and out on the member 13. The adjustable nipple-member 14, carries a wheel 15, by means of which the nipple member 14 is rotated, and this wheel has its periphery provided with numerals 75 16, indicating heat degrees. The nipple-member 13 extends from a suitable housing 17 and with which the gas-supply pipe 11 communicates. This housing 17 has a suitable hand-operated valve 18, by means of which the gas is shut off from or admitted to the said nipple members 13 and 14.

In the illustrative form here shown of my present improvement, the outer end of the nipple-member 14 has a contracted valve 85 seat 19. An internal valve 20 co-operating with the valve seat 19 and the said valve is connected with a rod 21, which passes through the deflected part 10 of the burner 9, and has its outer end 22 connected with 90 the lower end of the thermostat 3.

The thermostat 3 is of that well-known type which has its lower end moved back and forth by a variation in temperature. In the form here shown, the lower end of 95 the thermostat 3 will move in the direction indicated by arrow in Fig. 3, when it is heated and will move in the opposite direction when its temperature is lowered.

From this construction, it will be observed that the adjustment of the nipple-member 14 will carry its valve seat nearer to or farther away from the valve 20, according to the direction it is turned.

It will also be understood from this construction that the greater the distance between the valve 20 and its seat 19, the greater amount of heat will be required to seat the valve and shut off the gas that is flowing through the nipple member 14 and 110

out of the valve seat 19 thereof. Therefore, the relative adjustment of the valve 20 and the nipple-member 14 will determine the amount of heat required to cause the thermostat to move the valve 20 to closed position. By reason of this arrangement and construction, the parts will be so adjusted that when the regulating wheel 16 has a numeral 300 at the pointer 23, it will require three hundred degrees of heat in the oven to close the valve. A pilot light pipe 24 is connected with the lower end of the housing 17, and has its burner end 25 adjacent the oven burner 9, which pilot is burning all the time that the valve 18 is open to supply gas. If the heat in the oven rises to a degree that closes the valve 20, thereby shutting off the flow of gas to the burner 9, thus extinguishing it, the cooling of the valve will cause the valve 20 to open, and gas supplied to the burner 9. When this happens the pilot 25 lights the burner 9, so that the device is again operating to maintain the predetermined degree of heat. The regulating wheel is provided with a projection 26 that will prevent the wheel from being rotated more than one revolution in either direction by striking the pointer 23. The object of this is to prevent the nipple member 14 from being thrown out of its adjustment. That is to say, if it was turned more than one revolution in either direction, its adjustment would be destroyed.

The foregoing construction is simple and cheap and yet effective in its operation, and it is capable of being applied to the ordinary stove with practically no change in the stove.

Having thus described my invention, what I claim and desire to secure by Letters Patent is:

1. A fuel control for ovens, comprising an oven, a thermostat within the oven, an oven burner, a fuel supply for the burner comprising a gas-outlet and a valve controlling the outlet, a hand operating device independent of the thermostat for adjusting the

outlet in respect to the valve, and the valve operatively connected with the thermostat, the parts combined for the purpose described.

2. A fuel control for an oven, comprising an oven, a thermostat within the oven, an oven burner, a fuel supply for the burner comprising an adjustable nipple having a gas outlet opening, a valve for controlling the opening operatively connected with and operated by the thermostat, and a regulating member connected with the adjustable nipple, for the purpose described.

3. A fuel supply for ovens, comprising an oven, a thermostat within the oven, a burner, a rotatable and longitudinally adjustable gas-supply nipple having an outlet, a movable valve for controlling the outlet, the valve operatively connected with the thermostat, and a regulating member connected with the adjustable nipple, for the purpose described.

4. A fuel supply for ovens, comprising an oven, a thermostat within the oven, a burner, a hollow longitudinally adjustable nipple having a contracted end with an opening, a valve wholly within the nipple for controlling the opening, a connection between the thermostat and the said valve, and a regulating member directly connected with the adjustable nipple, for the purpose described.

5. A fuel control for ovens, comprising an oven, a thermostat within the oven, a burner, a fuel supply for the burner comprising a stationary externally screw-threaded nipple member, a movable nipple member inclosing the stationary one and screw threaded thereto, a regulating member connected with the movable nipple member, the movable nipple member having a gas outlet, a valve controlling the said outlet, and a connection between the valve and the thermostat, for the purpose described.

In testimony whereof I hereunto affix my signature.

BENJAMIN EDWIN MEACHAM
